DRILL BOOM STRUCTURE

This invention relates to swingably mounted drill boom structures of the type provided with a boom head for positioning a carrier of a feed bar for a rock drill into various angular positions with respect to a working surface.

Such drill booms mounted on a mobile substructure are usually used for drilling parallel holes in a working surface such as an end wall of a tunnel. When the feed bar is tiltable and laterally pivotable only, the boom itself will be an obstacle to positioning the feed bar to some positions. That is to say, there will be a "blind area" in the working surface. If the feed bar is displaceable with respect to the boom, this blind area is lessened or completely avoided.

For this reason, some previous booms of this type have been equipped with means for turning or rotating the boom head on the boom. In these previous embodiments the feed bar does not remain in its angular direction during turning unless it is in a specific position with respect to the boom. Therefore, the feed bar must normally be repositioned manually after a turning.

It is an object of the invention to provide a drill boom structure of the above-stated type which has the feed bar displaceable with respect to the boom in such a way that the boom remains in its angular direction when it is displaced.

For these and other purposes, there is provided a drill boom structure comprising a boom arranged at one end for lateral and vertical swinging on a substructure, a boom head at the opposite end of said boom arranged on said boom for motor actuated swinging about a first axis, a carrier pivotably mounted on said boom head for swinging about a second axis perpendicular to said first axis, and a feed bar for guiding a rock drill in a feeding direction mounted on said carrier, said carrier comprising a motor actuated hinge means for swinging said feed bar about a third axis, which is perpendicular to said second axes and parallel with said feeding direction.

The above and other objects of the invention are obvious from the following description and the accompanying drawings in which four preferred embodiments of the invention are illustrated by way of example. It should be understood that these embodiments are only illustrative of the invention and that various modifications may be made within the scope of the claim.

The invention is described with reference to the drawings in which FIG. 1 is a horizontal view, partly in section, of the outer part of a drill boom structure according to the invention, FIG. 2 is a section of line 2-2 in FIG. 1, FIG. 3 is an end view on line 3-3 in FIG. 1, FIG. 4 is a section of a hydraulic lock, which in FIG. 1 is shown applied to the boom structure, FIGS. 5 and 6 are vertical views of two modified drill boom structures according to the invention, FIG. 7 is an end view on line 7-7 in FIG. 6, FIG. 8 is an end view of a modified form of the boom structure shown in FIGS. 6 and 7, and FIG. 9 is a horizontal view of the boom structure in FIG. 8. In all the FIGS. corresponding details are given the same reference numeral.

In FIGS. 1-3 there is shown the outer end of a boom 10, which is laterally and vertically swingable by means of suitable hydraulic cylinders, which are not shown. On a boom head 11 on the boom 10, there is mounted a carrier 12 for a feed bar 13 guiding a rock drill 14. The boom head 11 is tiltable on a horizontal pivot 15 by means of a rod 17 in a way as will be described with reference to FIG. 5. Laterally, the feed bar carrier 12 pivots on a pivot 16 by means of a hydraulic swing cylinder 19.

The rock drill 14 is slidably mounted on the feed bar 13 and fed by a chain feed means 20 (FIG. 2) in a well known manner. The feed bar itself is axially slidably mounted on a plate 22 which is made rigid by means of side plates 21. A feed bar mover in the form of a hydraulic cylinder 23 provides the axial movement of the feed bar. The plate 22, which is a part of the carrier 12, is affixed to an end part or journal member 24, which embraces one end of a casing 25 for a turning means or motor means 30 and is rotatably journaled on the casing 25. The cylinder 19 for swinging the carrier 12 on the boom head

11 is connected to a support 31 screwed to the casing 25, which by means of lugs 27 is mounted on the vertical pivot 16. The plate 22 is fixed also to the upper half of an axially divided sleeve or journal member 26, which is journaled on the casing 25 and axially fixed by a stop lug 28 and a flange 29 on the casing 25. The casing 25 and the journal members 24, 26 thus provide a hinge means for swinging a part 24, 26, 21, 22 of the carrier with respect to another part 25, 31 of the carrier. In FIG. 3, the feed bar 13 is shown turned into two alternative positions.

In the turning means 30, FIG. 1 there is generated torque by a drive screw 32 which by helical splines is in engagement with corresponding splines in a turning nut 33. The drive screw 32 forms a piston rod of a piston 34, which is slidably and sealingly guided in a cylinder sleeve 35. The cylinder sleeve 35 is affixed by screws to a cylindrical base head 36 into which the piston 34 projects slidably but nonrotatably with a piston rod 37 provided with straight splines cooperating with corresponding splines in the head 36. The head 36 is screwed to the end flange 29 of the casing 25 and is closed by a cover 38.

The cylinder sleeve 35 fixedly carries a bearing member 40 in which a driving member 41 is rotatably journaled. The driving member is carried by a radial ball bearing 42 and is fixed axially at a central flange 43 between two axial ball bearings 44. The bearing member 40 and its bearings 42, 44 are covered by a cover 45 screwed to the bearing member 40 and sealed by suitable rings with respect to the rotatable driving member 41. At the end of a hollow member 46 of the driving member which projects into the drive end of the cylinder sleeve 35 the driving member 41 carries the turning nut 33.

A splined end 47 of the driving member 41 protruding from the cover 45 mates with splines in the end part 24 for rotating the latter. To the bearing member 40 is connected a pressure fluid conduit 48¹ by means of which pressure fluid can be supplied via suitable interior channels and openings in the bearing member 40 to the drive end of the cylinder sleeve 35 and to the interior of the hollow member 46 via bores in the driving member 41. By means of another pressure fluid conduit 49¹ pressure fluid can be supplied via suitable interior channels in the base head 36 to the base end of the cylinder sleeve 35 and the interior of the head 36. The conduits 48¹, 49¹ are connected to a hydraulic lock means which by means of conduits 48¹¹, 49¹¹ is connected in a conventional manner to a source of hydraulic pressure, not shown, via a control valve preferably of four way type and likewise not shown which closes the conduits 48¹¹, 49¹¹ or opens one of them optionally to high pressure and the other for return flow.

When pressure fluid is supplied to the conduit 49¹, the cylinder chamber at the base end of the cylinder sleeve 35 is pressurized as well as the interior of the base head 36. As a result the piston 34 is moved from the base head 36 by pressure acting upon the piston and upon the piston rod 37 simultaneously with pressure fluid in front of piston 34 and drive screw 32 being expelled via the conduit 48¹ and the drive screw 32 urging rotation of the nut 33. Thus the driving member 41 is forced to rotate in the bearing member 40 and its rotation is transmitted by its splines to the end part 24 so that the feed bar 13 can be adjusted to the desired angle about the longitudinal axis of the driving member. During angular adjustment, reaction torque caused by the torque generated between the drive screw 32 and the turning nut 33 is transmitted via the splines of the piston rod 37 to the base head 36 and thereby to the casing 25 and the boom head 11. Obviously, when pressure fluid is supplied to the conduit 48¹ the drive end of the cylinder sleeve 35 and the interior of the hollow member 46 of the driving member 41 are pressurized. This causes return of the piston 34 with its drive screw 32 and piston rod 37 simultaneously with pressure fluid being expelled from the base end of the cylinder sleeve 35 and the interior of the base head 36 via the conduit 49¹.

In order to increase the torsional rigidity of the hinge means in the various adjusting positions thereof, there is used a hydraulic lock means 50 working on spring loaded check

valves 51, 52, FIG. 4. The check valves 51, 52 take up closed position and prevent return flow from the conduits 48¹, 49¹ when low pressure is maintained in the conduits 48¹¹, 49¹¹ and the control valve, not shown, is in neutral position. Thus the piston 34 will be retained rigidly and hydraulically arrested in any adjusted position between one end position in which it abuts against the base head 36 and the other end position in which it abuts against the hollow member 46. As soon as high pressure is admitted to any of the conduits 48¹ or 49¹ by actuation of the control valve, a piston slide 53 slidably inserted in the hydraulic lock 50 between said conduits 48¹¹, 49¹¹ opens by the aid of a pushing rod and by way of forced motion the particular check valve 51 and 52 which is to be passed by return flow to the other conduits 49¹¹ or 48¹¹.

In FIG. 5, there is shown a boom structure having a boom of the type shown in FIG. 1. The feed bar carrier, the turning means and other details are principally as described with reference to FIG. 1, but the boom head 11 is modified so that the feed bar carrier 12 is arranged vertically off set the boom 10 instead of laterally off set. By the aid of the swing cylinder 19, the feed bar carrier 12 may be swung on the pivot 16. Normally, this pivot is vertical but it may be tilted together with the boom head 11 on the horizontal pivot 15 by lengthening or shortening the rod 17 by means of a hydraulic cylinder 18 integral with the rod 17. The boom is universally swingable on suitable pivots by means of cylinders 56, 57. Reference numeral 58 refers to a substructure or boom support. During vertical swinging of the boom 10, the boom head 11 and thus the feed bar 13 will maintain its angular position by virtue of the rod 17. Such a parallel movement can also be provided by virtue of hydraulic control means, e.g. as described in U.S. Pat. No. 2,613,822.

In FIG. 6 there is shown another design in which the boom 10 comprises a first boom portion 10¹ and a second boom portion 10¹¹. The second and forked boom portion is telescopically and extendably carried by the first boom portion. A rod 17, as described, is therefore not suitable but the boom head is tiltable by means of a hydraulic cylinder 59. In this embodiment, the feed bar is mounted on two arms 60 on the journal members 24, 26. The mounting of the carrier 12 on the boom head 11 compares favorable with the arrangements shown in the preceding figures by permitting the hinge means 24, 25, 26 to turn at least 270°. At the arm of member 26, the feed bar is pivotally mounted on a transverse pivot, not shown, and at the arm of member 24 it is mounted by means of a hydraulic cylinder 61. By this arrangement the feed bar may be adjusted out of alignment with the hinge means so that the outermost holes in an end wall of a tunnel may be directed for instance about 5° outwardly with respect to the other holes which normally are parallel and directed perpendicular to the end wall. In FIG. 8-9 there is shown a modified form of the drill boom in FIG. 6-7. In this embodiment there is a first hinge means arranged for swinging the arms 60 as described. This hinge means is given reference numeral 62. The arms, however, carries a second hinge means 63 for turning the feed bar 13 with respect to the arms. The feed bar may be mounted on the second hinge means by means of a hydraulic cylinder 61 as described with reference to FIGS. 6-7.

Although several embodiments of the invention have been illustrated and described in detail, it is to be understood that the invention is not limited thereto.

We claim:

1. A drill boom structure comprising a boom arranged at one end for lateral and vertical swinging on a substructure, a boom head at the opposite end of said boom arranged on said boom for motor actuated swinging about a first axis, a carrier pivotably mounted on said boom head for swinging about a

second axis perpendicular to said first axis, and a feed bar for guiding a rock drill in a feeding direction mounted on said carrier, said carrier comprising a motor actuated hinge means for swinging said feed bar about a third axis, which is perpendicular to said second axes and parallel with said feeding direction.

5 2. A drill boom structure according to claim 1 in which a motor means for actuating said hinge means includes a pressure fluid actuated piston, which is sealingly guided for reciprocation in a cylinder and has piston rod means slidably connected to a first member of the carrier by a splined connection and piston rod means slidably connected to a second member of the carrier by a splined connection having screw splines, said first and second member of the carrier being rotatively journaled to each other for providing the hinge means.

10 3. A drill boom structure according to claim 2 in which said first part of the carrier comprises a cylindrical housing for the motor means mounted on said boom head and said second part of the carrier comprises a support rotatably journaled on said cylindrical housing, said support extendably carrying the feed bar.

15 4. A drill boom structure according to claim 1 in which the boom comprises a first boom portion, which is mounted on the substructure, and a second boom portion, which is parallel with and extendably supported by said first boom portion and carries the boom head.

20 5. A rock drill boom structure comprising a boom having one end universally pivotally connected to a mounting, a boom head pivotally mounted at the opposite end of the boom for swinging about a first axis, a first member pivotally mounted on the boom head for swinging about a second axis, which is perpendicular to said first axis, a second member swingably carried by said first member for swinging about a third axis, which is perpendicular to said second axis, a feed bar for a rock drill which is extendably supported by said second member and has a longitudinal axis substantially parallel to said third axis, motor means for swinging the boom laterally and vertically relative to said mounting, a motor means for swinging the boom head about said first axis, a motor means for swinging said first member about said second axis, and a motor means for swinging said second member about said third axis.

25 6. A rock drill boom structure comprising a boom arranged at one end for lateral and vertical swinging on a substructure, a boom head at the opposite end of said boom arranged on said boom for motor actuated swinging about a first pivot providing means, a carrier pivotably mounted on said boom head for swinging about a second pivot providing means, which is perpendicular to said first pivot providing means, and a feed bar for guiding a rock drill mounted on said carrier, which comprises a first motor actuated hinge means arranged on said head and a second motor actuated hinge means swingably carried by said first hinge means and swingably carrying said feed bar, said first and second hinge means and the feed bar being substantially parallel to each other but perpendicular to said first and second pivot providing means.

30 7. A rock drill boom structure comprising a boom connected at one end to a substructure so as to be pivotal about a horizontal axis and about a vertical axis, motor means for swinging said boom about said horizontal axis, motor means for swinging said boom about said vertical axis, a boom head at the opposite end of the boom, a first hinge means arranged on said head, a second hinge means swingably carried by said first hinge means and arranged laterally thereof, and a feed bar for guiding a rock drill swingably carried by said second hinge means, the axes of the first and second hinge means and said feed bar being substantially parallel.
